UNITED STATES PATENT OFFICE.

CARRIE S. RATTAN, OF SAN FRANCISCO, CALIFORNIA.

GARMENT HANGER.

1,422,782.

Specification of Letters Patent. Patented July 11, 1922.

Application filed September 6, 1921. Serial No. 498,756.

To all whom it may concern:

Be it known that I, CARRIE S. RATTAN, a citizen of the United States, residing at San Francisco, in the county of San Francisco 5 and State of California, have invented new and useful Improvements in Garment Hangers, of which the following is a specification.

This invention relates to wearing-apparel 10 apparatus and has for its primary object to provide an improved garment hanger equipped to support one or more garments such as coats, skirts and the like.

Another object of this invention is to provide a device of the character described 15 which comprises a plurality of supporting bars having a connection therebetween, whereby the said bars may be readily folded one upon the other to save space in packing 20 when the hanger is not used for the purpose of supporting clothes.

A further object of this invention is to equip one of the bars of the hanger with means, whereby the said bars may be readily 25 adjusted to fit various sizes of skirts and the like.

A still further object of this invention is to provide a device of the character described, which is simple in construction, 30 economical to manufacture, strong and durable and so constructed as to be able to support a number of garments of different shapes, and sizes.

Other objects and advantages will be apparent during the course of the following description.

In the accompanying drawings forming a part of this specification and in which like numerals are employed to designate like 40 parts throughout the same,

Fig. 1 is a front elevation of my improved hanger,

Fig. 2 is a transverse vertical section taken on the line 2—2 of Figure 1, and

Fig. 3 is a similar view taken on the line 3—3 of Figure 1.

In the accompanying drawings wherein for the purpose of illustration is shown a preferred embodiment of my invention, the 50 numeral 5 designates a supporting bar of the usual curved shape, preferably made of wood. The supporting bar is centrally bored as at 6 in order to receive therein a shank 7, which terminates adjacent its upper extremity in a hook 8 and at its lower ex-

tremity in a loop 9. The supporting bar is preferably slotted as at 10 so as to be able to mount thereon metal straps 11 which terminate adjacent their lower extremities in curved ends 11'. On the supporting bar 5 60 I propose to hang a garment such as a coat, while the straps 11 which are connected to the bar, can be utilized to support a number of other articles of wearing apparel.

Adapted to be connected to the loop 9 is 65 the upper extremity of a cord 12, which cord in turn has its lower extremity secured to a loop 13 of a depending shank 14 constructed of the same material as the shank 7, which material is preferably made of rigid 70 wrapped fabric and differs from the formation of the cord 12, inasmuch as the cord 12 can be readily folded back upon itself when it is desired to fold the hanger for the purpose of packing or shipping. The shank 14 75 is likewise received in a centrally located bore 15 of a lower or second supporting bar designated as a whole by the numeral 16. This supporting bar is likewise of the usual curved shape and is located below the supporting bar 5 and extends in the same plane therewith.

As shown to advantage in Figures 1 and 3 it will be observed that the supporting bar 16 embodies in its construction an intermediate bar 17, preferably made of metal and having provided therein slots 18, two of which slots continue into spaced notches 20 and 21. The extremities of the bar 17 are adapted to be received in the end pieces 22 90 and 23, preferably made of wood, of the second or lower supporting bar and are retained from displacement therefrom by cross pins 24, on which are supported a second set of straps 25, or similar construction as 95 the straps 11.

From this construction it will be apparent that the lower supporting bar 16 can be made readily adjustable to fit various sizes of garments such as skirts and that the limit of 100 the expansion of the end pieces 22 and 23 can be regulated by the disposition of the pins 24 in the notches 18 and of the intermediate metal bar 17.

In order that there may be no danger of 105 the skirt being displaced from the sections 22 and 23, I propose to threadedly mount on the top of the sections pegs 26 and 27. The skirt as it is draped over the bar 16 can then be secured to these pegs, and thus there will 110

be eliminated the possible danger of the skirt being accidentally displaced from the supporting bar 16. These pegs are preferably made detachable so that the bar 16 can 5 likewise serve for a coat hanger, if so desired.

By employing means for connecting the two bars such as the cord 12, it will be further evident that the bars 5 and 16 can be 10 readily folded one upon the other when it is desired to pack the device for travel.

From the foregoing construction as just described it will be evident that I have devised an exceptionally strong and durable 15 garment hanger which can be made of comparatively few parts, and which can be readily assembled and disassembled.

It is to be understood that the form of my invention herewith shown and described, is 20 to be taken as a preferred example of the same, and that various changes in the shape, size and arrangement of parts may be resorted to without departing from the spirit

of the invention or the scope of the subjoined claim.

Having thus described my invention, I claim:

In a garment hanger, a supporting hook having a depending shank, a curved supporting bar mounted on said shank, laterally 30 sliding hooks supported by said curved support, a second curved supporting bar suspended below said first mentioned curved supporting bar, said second curved supporting bar being of a length equal to the first 35 mentioned supporting bar, slots formed in said second mentioned supporting bar, end pieces adapted to be slidably held on said second mentioned supporting bar, cross-pieces extending therethrough and adapted 40 to pass through said slots, and means carried at the outer ends of said end pieces for retaining a garment thereon.

In testimony whereof I, affix my signature.

CARRIE S. RATTAN.
